UNITED STATES PATENT OFFICE.

DAN O'NEIL, JOHN A. HOLMQUIST, AND JOHN W. FREE, OF WOODLAWN, PENNSYLVANIA, ASSIGNORS TO JONES & LAUGHLIN STEEL COMPANY, OF PITTSBURGH, PENNSYLVANIA, A CORPORATION OF PENNSYLVANIA.

MACHINERY FOR REMOVING SUPERFLUOUS SPELTER FROM GALVANIZED ARTICLES.

1,338,152.

Specification of Letters Patent.

Patented Apr. 27, 1920.

Application filed December 27, 1919. Serial No. 347,861.

To all whom it may concern:

Be it known that we, DAN O'NEIL, JOHN A. HOLMQUIST, and JOHN W. FREE, residing at Woodlawn, in the county of Beaver and 5 State of Pennsylvania, citizens of the United States, have invented or discovered certain new and useful Improvements in Machinery for Removing Superfluous Spelter from Galvanized Articles, of which improvements 10 the following is a specification.

Our invention relates to improvements in machinery for separating the components of the masses of composite material and particularly for removing the superfluous coating material from articles coated by immersion; specifically, our improved machinery finds practical use in removing from such 15 small galvanized iron articles as nails the superfluous zinc adhering to them as they 20 come from the galvanizing bath. Tumbling barrels and centrifugal separators have heretofore been employed for this purpose, and the machine of our present invention, differing from those in structure and operation, 25 has for its ends an even coating of the galvanizing metal over the surface of the article and at the same time such high rapidity of production as to adapt it peculiarly well to the conditions and demands of 30 mill practice.

Our invention is illustrated in the accompanying drawings, in which Figure 1 is a view of the machine of our invention in horizontal section, and Fig. 2 a view of it in 35 vertical section. The plane of section of Fig. 2 is indicated by the dotted line II-II, Fig. 1, and the plane of section of Fig. 1 is correspondingly illustrated by the broken dotted line I-I, Fig. 2.

We shall, in the ensuing description, confine attention to the removal of superfluous zinc from newly galvanized nails ordinarily made of steel wire, but it will be understood from what has gone before that the machine 45 is by no means limited to particular articles nor to particular materials; and we mean to bring within the scope of the ensuing claims machinery for accomplishing such separation, without the limitations of the nature 50 suggested.

The ordinary process of galvanizing nails is effected by filling a perforated ladle with

the uncoated nails as they come from the nail machine, dipping the filled ladle into a bath of molten zinc, and allowing it to remain in the bath for a sufficient time for the zinc to penetrate and percolate through the mass of nails within the ladle. The ladle is then removed, and one of two methods of procedure is then ordinarily pursued; either 55 the nails are turned from the ladle into a tumbling barrel, or the ladle itself is mounted on an axle and rotated at high speed, and the superfluous metal is thrown out through the perforations as the ladle rotates. 60

We have found it advantageous, in this preliminary step of the procedure, to use a small ladle rather than a large one; for thus we insure rapid penetration of molten spelter throughout the whose mass of nails within the ladle, and rapid penetration of heat throughout the mass. Rapid penetration of zinc, and temperature above the melting point of zinc, rapidly attained throughout the mass, are desiderata, making for the 65 70 75 rapid turning out of a product of good and even quality.

The mass within the ladle, on being raised from the bath of spelter, is in somewhat such condition as a mass of tooth-picks might be 80 understood to be, after immersion, and on being lifted out of water; not only are the nails wet and coated over with zinc, but superfluous zinc is carried in the interstices between them. This superfluous zinc is of 85 course to be removed and the nails are to be left, each separate from the others, and each evenly coated; and such removal of superfluous zinc will manifestly be accomplished to advantage, if it is accomplished before the 90 cooling zinc "freezes" and solidifies the mass. The speed varies according to the size of the nails.

The ladle full of nails is brought to a separating machine; and it is in the particular construction of the separating machine which now we are about to describe that our invention resides. We shall describe the progress of the nails through the machine, and in the course of this description the structure of the machine in all its essential features will be made plain. The ladle is brought to the machine, and the charge is dumped into it through a hopper 95 100

1 at the top. This hopper delivers the charge through a central opening in the top of the machine. Passing through the opening, the charge is spread by the conical bell 2, arranged immediately beneath the opening, and falls upon the wheel 3. This wheel is mounted upon a vertical axle, and through that axle by means not shown is caused to rotate at a speed sufficient to effect 10 the ends to be described. The wheel is provided with radial vanes or paddles 4, which, bearing upon the dumped-in material, carry that material forward with the wheel in its rotary course. Because of the rapid rotation of the wheel 3, the dumped-in material, acquiring rotary motion, immediately, under centrifugal force, flies out from the periphery of the wheel. Encircling the wheel, and standing opposite its periphery 15 with a narrow interval between, is a wall 5; the wall is preferably, though not necessarily, conical in shape, and downwardly-flaring, as shown. The material thrown out from wheel 3 in the manner described 20 strikes against this wall, and falls to the hopper 6 arranged beneath; from the hopper the material slides and is delivered to an inclined chute 7. Adjacent the delivery edge of chute 7, and spaced from it at a 25 narrow interval, is a magnetic conveyer. This magnetic conveyer consists of an endless belt 8 traveling on a gentle incline as shown and sustained adjacent the delivery chute 7 by a magnetized roller 14. Such 30 magnetized rollers, and magnetic conveyers so constituted are to be had in the market, and require no detailed consideration.

By virtue of the space between the edge 35 of chute 7 and the face of the belt 8 upon 40 the magnetized roller 14 the non-magnetic material, that is to say, the bits of spelter, will fall by gravity, while the nails themselves, being of magnetic material, will be drawn to and cling to the belt, and will be 45 carried by the belt 8 to the place of delivery. The chute 7 is a jig-chute, in that the material descending over it is shaken and caused to dance upon it, in consequence of rapidly repeated sharp jars or vibrations 50 imparted to it. Our convenient arrangement in this detail is this: The chute itself, preferably formed of metal, is supported midway its length (and preferably at that point only) by resting on a block 9 (con- 55 veniently of wood), which block 9 is carried on slats 10 (also conveniently of wood). The slats are secured at one end to the beam or sill 11 and at the other end they rest upon cams 12 borne by a rotating shaft 13. 60 The effect of rotation is a sharp bumping or knocking which, imparted to the material descending over chute 7, causes it to dance in the manner mentioned above.

Returning now to the material charged in 65 and to the effect upon it of these several

instrumentalities, it will be understood that the effect of impact of the material slung from wheel 3 against wall 5 will be to disintegrate the mass and to shake from the nails the superfluous spelter, to loosen the 70 nails one from another, and (the temperature being now near or somewhat lower than the melting point of zinc) to permit a smooth and even and unbroken coating to harden upon each nail, while the superfluous coating metal "freezes" into disconnected particles. The now disintegrated mass of solid bodies of two kinds descending, passes over the jig-chute 7, by dancing upon this chute, the tendency of the nails to accumulate in masses is overcome, and instead the material is spread loosely over the chute. As the material passes over the edge of the chute, the nails are picked up by the magnetic conveyer, and carried away from the 80 bits of spelter which fall from the edge of the chute.

We do not limit ourselves in the matter of detail in mechanical construction, but mean to include within the scope of the ensuing claims machinery possessing the characteristics and accomplishing the ends defined.

We claim as our invention:

1. A separator for masses of composite material consisting essentially of a rotary member adapted to receive and to carry and to deliver under centrifugal force from its periphery material fed to it in bulk, an encircling wall adapted to arrest the centrifugal travel of the material thrown from the rotary member and by such arrest to disintegrate the material, and means for separating the disintegrated material, part from part, substantially as described. 95

2. A separator for masses of composite material partly solid and partly in course of solidification, consisting of a rotary member adapted to receive and to carry and to deliver under centrifugal force from its periphery material fed to it in bulk, an encircling wall adapted to arrest the centrifugal travel of the material thrown from the rotary member and by such arrest to disintegrate the material, and means for separating the disintegrated material, part from part, substantially as described. 100

3. A separator for articles of magnetic material integrated with another material, consisting of means for disintegrating the material, a jig-chute adapted to receive the material from the disintegrating means, and a magnetic conveyer arranged at an interval from the delivery edge of said chute, substantially as described. 115

4. Apparatus for separating superfluous spelter from a mass of galvanized articles of magnetic material on removal from the galvanizing bath, including a rotary member adapted to receive and to carry and to 120

deliver under centrifugal force from its periphery material fed to it in bulk, an encircling wall adapted to arrest the centrifugal travel of the material thrown from the 5 rotary member and by such arrest to disintegrate the material, and a magnetic separator adapted to act upon the disintegrated material fallen from said wall, substantially as described.

In testimony whereof we have hereunto set our hands.

DAN O'NEIL.
JOHN A. HOLMQUIST.
JOHN W. FREE.
